R. L. COONEY.
STATIONARY FIRE EXTINGUISHER SYSTEM.
APPLICATION FILED SEPT. 24, 1909.

1,075,014.

Patented Oct. 7, 1913.

UNITED STATES PATENT OFFICE.

ROBERT L. COONEY, OF ATLANTA, GEORGIA.

STATIONARY FIRE-EXTINGUISHER SYSTEM.

1,075,014.

Specification of Letters Patent.

Patented Oct. 7, 1913.

Application filed September 24, 1909. Serial No. 519,420.

To all whom it may concern:

Be it known that I, ROBERT L. COONEY, a citizen of the United States, residing at Atlanta, in the county of Fulton and State 5 of Georgia; have invented new and useful Improvements in Stationary Fire-Extinguisher Systems, of which the following is a specification.

This invention relates to improvements 10 in stationary fire extinguisher systems.

The primary object of the invention is the combination with a stationary fire extinguisher system of a novel hose cabinet attachment. In this respect the invention 15 contemplates an arrangement especially applicable to the stationary systems of large office buildings, hotels, apartments, etc., whereby the opening of the door of the cabinet or the manual withdrawal of the hose 20 from the cabinet, produces the operation of the system. The arrangement is to be preferred to ordinary distributing valves since its operating parts are concealed, may be locked if desired against unauthorized access, are not subject to accidental operation 25 or to the experiments of "meddlers" or "loafers" and provide (in the case of pressure controlled systems) double assurance of the operation of the system, since 30 if the pneumatic impulse incident to the opening of a distributing valve is insufficient to produce the operation of the system, additional means operable subsequently to the opening of the distributing 35 valve is employed to produce the operation of the system in a certain manner.

A further object of the invention is to provide as an adjunct of a system of the general type which forms the subject 40 of my co-pending application Serial Number 540,661, a means or device located at the vent of the distributing pipe for creating a suction influence in the latter which influence is transmitted by the distributing 45 pipe to the plunger which controls the discharging operation of the acid bottle and causes an operative movement of said plunger.

A preferred and advantageous embodiment 50 of the invention is shown by way of example in the accompanying drawings.

In the said drawings: Figure 1 is a sectional view showing the application of the arrangement to a system of pressure control. 55 Fig. 2 is a perspective view of the cabinet and the adjunctive mechanism inclosed

therein. Fig. 3 is a horizontal sectional view of the cabinet.

Similar characters of reference designate corresponding parts throughout the several 60 views.

The invention is shown, by way of example, as carried out in connection with the system or apparatus which forms the subject of my co-pending application Serial 65 Number 540,661 and which therefore need be described only in a general way. Said system or apparatus includes a tank, as 1, which is connected to a distributing pipe 2 by a "secondary" shell, as 3, to which 70 a barrel, as 4, is connected. The barrel 4 projects into the tank 1 and therein is provided with a depending pipe, as 5, through which the fire extinguishing agent flows to the distributing system. Within 75 the barrel 4 is a rod, as 6, which projects inwardly into the tank through an enlarged opening in the end of the barrel. The rod 6 is provided with a head 8 which works in the shell 3 and normally closes the end of 80 the barrel 4 and also with a head 9, within the tank 1, and which, when the system is working, closes the aforesaid enlarged opening. The system shown is of the chemical mixing type and includes an invertible acid bottle, as 10, which, upon inversion, discharges its contents into a body 85 of alkaline solution contained in a tank. The generation of a gas fatal to combustion then ensues in the well known manner. 90 The bottle 10 is operatively connected to the rod 6 by a chain, as 11. In this arrangement the tank and the system are connected by a branch pipe, as 14, which has an apertured diaphragm or its equivalent, as 95 15. By virtue of the construction detailed, pressure introduced into the distributing pipe from any suitable source (not shown) will enter the shell 3 and likewise, owing to the provision of pipe 14, will also enter 100 the tank 1 to an equal degree. The apertured diaphragm 15 maintains the pressure in the tank normally equal to that in the distributing pipe and in the shell 3, thus compensating for slight leakages from any 105 cause whatsoever, but, should a distributing valve be opened, the pressure in the pipe 2 and in the shell 3 will be suddenly and materially reduced. The apertured web 15 will not compensate for this sudden and 110 material reduction of pressure, and, therefore, the pressure in the tank 1 retains most

of its force and, passing through the aforesaid large opening in the barrel 4, acts on the head 8, forcing the same and therewith the rod outwardly. As a consequence of this operation the acid bottle is inverted, and generation is set up.

The foregoing system is to be considered merely as exemplary of one application of the invention. It is not obligatory and other types of systems and constructions may be employed within the purview of the invention.

The construction which is exemplary of the present invention includes a cabinet, as 16, which may be attached to the wall or other suitable support and which incloses a line of flexible hose, as 17, and a distributing valve, as 18, the latter being provided at the end of a branch pipe 19 which is joined to the pipe 2 and projects through a wall of the cabinet 16. The valve 18 has a coupling which provides for the operative connection with the valve of one end of the hose line 17. The hose at its other end has the usual nozzle 20 which, in the present instance, is provided with a piston head 21. A cylinder, as 22, is shown as depending from the top of the cabinet and has its upper end closed and its lower end open. The nozzle 20 is supported in this cylinder by a spring clip 23 of suitable form and its piston head 21 contacts with the inner face of the cylinder. The closed upper end of the cylinder is provided with an outwardly opening check valve 20^a, which, when the nozzle is inserted with the cylinder, prevents the compression of air in the distribution pipe but provides for the creation of a suction influence in the distributing pipe when the nozzle is withdrawn as will be hereinafter explained.

The valve 18 is operated by means of an arm, as 24, which is secured to the stem of the valve and in the closed position of the valve is disposed parallel to the front and rear walls of the cabinet. The front wall, designated by the numeral 25 and constituting a door, is hinged to one of the side walls of the cabinet and at its free side may be provided with a knob or hand grip 26 having a latch arm 27. If desired, any approved lock may be substituted for this arrangement. The door 25 is also provided on its inner face with an inwardly projecting pivoted catch, as 28, which is normally held in a horizontal position, being capable of upward movement but incapable of downward movement from said position. When the door is closed the bill of the catch 28 automatically engages over the arm 24 and it follows that when the door is opened the arm 24, by virtue of the engagement of the catch 28 therewith, will be swung outwardly as indicated in dotted lines in Fig. 3, and the valve 18 thereby opened. When

this action has taken place, if the system herein described is employed and has a normal charge of air or gas under pressure, such air or gas flowing through the hose line 17 will expand in the cylinder 22 and will thereby act against the piston head 21 and force the same and therewith the nozzle 20 from said cylinder. The expansion of the air or gas incident to the opening of the valve 18 will also produce the unbalancing of the pressure forces and the consequent operation of the system in the manner explained.

In case the system is dormant, *i. e.* without air or gas, either by reason of the failure to originally charge the same or on account of leakage, the opening of the valve 18 is without effect in so far as producing the operation of the system is concerned. In such a case the operation of the system is produced by the manual withdrawal of the nozzle 20 and piston head 21 from the cylinder 22, such withdrawal causing a suction influence in the hose line, the pipe 2 and the barrel 3 and this positively induced suction influence causing the operative movement of the head 8 and therewith of the rod 6, as a consequence of which the system commences its operation in the manner previously described.

The invention is not limited in its purview to application to the particular system herein shown nor to the particular apparatus herein shown as illustrating the invented subject matter.

Having fully described my invention, I claim:

1. The combination with a line of hose, a distributing pipe connected thereto and a fire extinguisher system including chemical mixing means, of a cabinet inclosing the line of hose and provided with a movable normally closed door and means mechanically connected to the door and positively actuated thereby when the door is opened to govern the operation of the chemical mixing means.

2. The combination with a line of hose, a distributing pipe connected thereto and a fire extinguisher system including pressure controlled means for causing the flow of a fire extinguishing agent through the distributing pipe of a line of hose connected to the distributing pipe and having a nozzle, a piston head on the nozzle and a cylinder inclosing the piston head and providing for the creation of a suction influence in the distributing pipe to cause the operation of the system consequent to the withdrawal of the nozzle from the cylinder.

3. The combination with a line of hose, a distributing pipe connected thereto and a fire extinguisher system including means operable consequent to a fall of pressure in the distributing pipe for causing the flow

of a fire extinguishing agent through the distributing pipe, of a valve arranged at the connection of the distributing pipe and the hose, a cabinet inclosing the hose and the valve and having a movable normally closed door and means provided on the door for positively opening the valve consequent to the opening of the door.

4. The combination with a line of hose, a distributing pipe connected thereto and a fire extinguisher system including means operable consequent to a fall of pressure in the distributing pipe for causing the flow of a fire extinguisher agent through the distributing pipe, of a valve arranged at the connection of the distributing pipe and the hose, a cabinet inclosing the hose and the valve and having a movable normally closed door, means provided on the door for opening the valve consequent to the opening of the door, a cylinder in the cabinet to receive the nozzle of the hose, and a piston head fitted on the nozzle and disposed in the cylinder to develop a suction influence in the line of hose and distributing pipe consequent to the withdrawal of the nozzle.

5. The combination with a line of hose, a distributing pipe connected thereto and a fire extinguisher system including a tank with which the distributing pipe communicates, and an acid bottle arranged to dis-

charge its contents into the tank, the line of hose having a nozzle, of a cylinder in which the nozzle is normally fitted, and means associated with the nozzle and coöperating with the cylinder for causing a suction influence in the line of hose and the distributing pipe consequent to the withdrawal of the nozzle from the cylinder, the said influence acting to cause the discharging operation of the acid bottle.

6. The combination with a line of hose, a distributing pipe connected thereto and a fire extinguisher system including a controlling element which is operatively movable by a suction influence transmitted by the distributing pipe, the line of hose having a nozzle, of a cylinder in which the nozzle is normally fitted, and means associated with the nozzle and coöperating with the cylinder for causing a suction influence in the line of hose and the distributing pipe, consequent to the withdrawal of the nozzle from the cylinder.

In testimony whereof I have hereunto set my hand in presence of two subscribing witnesses.

ROBERT L. COONEY.
